UNITED STATES PATENT OFFICE.

ARTHUR TREVOR DAWSON AND GEORGE THOMAS BUCKHAM, OF WESTMINSTER, LONDON, ENGLAND, ASSIGNORS TO VICKERS SONS & MAXIM, LIMITED; OF WESTMINSTER, LONDON, ENGLAND.

ORDNANCE.

SPECIFICATION forming part of Letters Patent No. 743,466, dated November 10, 1903.
Application filed July 13, 1903. Serial No. 165,290. (No model.)

To all whom it may concern:

Be it known that we, ARTHUR TREVOR DAWSON, lieutenant of the Royal Navy and director and superintendent of Ordnance Works, and GEORGE THOMAS BUCKHAM, engineer, both subjects of the King of Great Britain, residing at 32 Victoria street, Westminster, in the county of London, England, have invented certain new and useful Improvements 10 Relating to Ordnance, of which the following is a specification.

This invention relates to ordnance of the kind in which the gun is adapted to recoil in a cradle having buffer-cylinders for checking 15 the recoil and returning the gun to battery.

The chief object of the invention is to provide means for enabling the gun to be quickly disconnected from the rods of the buffer-pistons and removed from the cradle when it is 20 desired to separate the gun and cradle for the purpose of forming them into convenient loads for conveyance over difficult country by draft-animals. We accomplish this object by forming the outer ends of the said piston-rods 25 with screw-threaded segments, flats, or other suitable means for enabling them to be readily engaged with the lugs on the gun by an angular movement of the rods imparted thereto by handles or other appropriate devices. 30 The rods may be prevented from unintentional angular movement for disengaging them by spring-clips or other suitable locking contrivances.

In the accompanying drawings, Figure 1 is 35 a sectional side elevation of the rear portion of the gun and its cradle constructed in accordance with our invention. Fig. 2 is a rear end elevation, and Fig. 3 a half-sectional plan, of the same.

40 The breech mechanism has been omitted from the foregoing figures for sake of clearness.

A is the gun, B the cradle, and B^x B^x are the brake-cylinders.

45 The gun is provided with the usual lugs A' A', by means of which it is connected with the piston-rods B' B' of the brake-cylinders. b is a handle, with which each of the rods B' is provided for turning the latter, said handle being in the example illustrated secured

to the rod by screw-threads in its boss engaging with corresponding screw-threads on the rod and by a transverse pin b' passing through said boss and rod. The portion of the rods B' that enters the lugs A' is in the example illustrated formed with interrupted screw-threads b², which when said rods are turned into the position represented by the full lines in Fig. 2 engage with corresponding interrupted screw-threads in the lugs A', thereby securing 60 the gun and buffer-pistons together, so that when the gun recoils in the cradle the buffers will act in the ordinary manner. When said handles b are turned into the position represented by the dotted lines in Fig. 65 2, the said rods B' will be turned into a position to disengage the aforesaid interrupted screw-threads on the rods from those of the lugs A', so that the gun and rods will be disengaged and the gun be free to be entirely 70 withdrawn and detached from its cradle.

In order to insure that the extent of angular movement imparted to the rods B' by the handles b shall not exceed that which is necessary for properly disengaging the interrupted screw-threaded rods from the lugs A', the boss of each handle may be provided with a finger b³, which will abut against a projection or cam-piece b⁴ on the cradle, Fig. 2, when the handles are turned to a sufficient 80 extent for effecting the aforesaid disengagement.

For the purpose of insuring that the rods shall not become unintentionally turned to disengage the parts we employ a catch device which in the example illustrated comprises a spring-clip a, hinged at a' to the gun and having a rectangular slot or opening a² therein for engaging with a correspondingly-shaped rectangular head b⁵ on the end of 90 each rod B'. When the rods are properly engaged with the lugs A', the said heads b⁵ lie in a position to enter the slots a² of the clips when the latter are turned inwardly—i. e., into the position represented in the drawings—so that the rods are prevented from turning again until the spring-clips have been moved into a position to release said heads b⁵. The said clips are retained in their locking position by the pressure of the springs 100

a^3 , acting upon washers a^4 , interposed between said springs and the flat portions a^5 of the clips.

We wish it to be understood that we do not confine ourselves to the above-described means whereby the rods B' are turned and their engagement with the lugs A' is effected and maintained, as said means may be varied without departing from the nature of our invention.

What we claim, and desire to secure by Letters Patent of the United States, is—

1. The combination with a recoiling gun, its cradle, buffers and buffer-piston rods, of means for connecting said piston-rods to the gun, means for effecting their disconnection by a partial rotary or angular movement, and means for temporarily holding the rods against rotary movement for the purpose specified.

2. The combination with a recoiling gun, its cradle, buffers and buffer-piston rods, of means for connecting and disconnecting said piston-rods to and from the gun by an angular movement of the rods, means for imparting said movement to the rods, and means for temporarily retaining the rods in their connected condition substantially as described.

3. The combination with a recoiling gun, its cradle, buffers and buffer-piston rods, of interrupted screw-threads on the said rods adapted to engage with corresponding interrupted screw-threads in the lugs of the gun by an angular movement, means for imparting to said rods their angular movement and means for temporarily retaining the rods in their position of engagement substantially as described.

4. The combination with a recoiling gun, its cradle, buffers and buffer-piston rods, of interrupted screw-threads on the outer ends of said rods adapted to engage with corresponding interrupted screw-threads in the lugs of the gun by an angular movement, handles on said rods for imparting to them their angular movement and clips for temporarily

retaining said rods in their position of engagement substantially as described.

5. The combination with a recoiling gun, its cradle, buffers and buffer-piston rods, of interrupted screw-threads on the outer ends of said rods adapted to engage with corresponding interrupted screw-threads in the lugs of the gun by an angular movement, handles on said rods for imparting to them their angular movement, means for limiting the extent of movement of said rods when turned in a direction to cause their disengagement with the lugs, and clips for temporarily retaining said rods in their position of engagement substantially as described.

6. The combination with a recoiling gun, its cradle, buffers and buffer-piston rods, of means for connecting and disconnecting said piston-rods to and from lugs on the gun by an angular movement, handles on said rods for imparting to them their angular movement, fingers on said handles adapted to engage with cam-surfaces on the cradle to limit the movement of said handles in turning to disengage the lugs, and clips for temporarily retaining said rods in their position of engagement substantially as described.

7. The combination with a recoiling gun, its cradle, buffers and buffer-piston rods, of means for connecting and disconnecting said piston-rods to and from lugs on the gun by an angular movement, means for imparting said angular movement to the piston-rods, spring-clipshinged to the said lugs and formed with slots, and heads on the said rods for engagement with said slots when the clips are turned into their locking position substantially as described.

In testimony whereof we have hereunto set our hands, in presence of two subscribing witnesses, this 30th day of June, 1903.

ARTHUR TREVOR DAWSON.
GEORGE THOMAS BUCKHAM.
